UNITED STATES PATENT OFFICE.

FRENCH S. EVANS, OF WASHINGTON, DISTRICT OF COLUMBIA.

DESIGN FOR A CANE HEAD OR HANDLE.

SPECIFICATION forming part of Design No. 25,851, dated **August 4, 1896.**

Application filed July 9, 1896. Serial No. 598,613. Term of patent 31 years.

To all whom it may concern:

Be it known that I, FRENCH S. EVANS, a citizen of the United States, residing at Washington, District of Columbia, have invented and produced a new and original Design for Cane Heads or Handles; and I do hereby declare the following to be a full, clear, and exact description of the same, reference being had to the accompanying drawings, forming a part thereof.

Figure 1 is a plan or top view of a cane head or handle, showing one part of my design. Fig. 2 is a side elevation of the head, showing the design for one side. Fig. 3 is also a side elevation of the head opposite to that shown in Fig. 2.

The leading features of the design consist in the convex medallions or busts in relief representing William McKinley and Garrett A. Hobart, the candidates of the Republican party for President and Vice-President, surrounded by an ornamental scrollwork, and the sides of the head or handle provided with the flag of the United States upon one face

thereof and upon the other face with the 25 figure of an elephant.

In the accompanying drawings, A represents the main part or body of the cane, and B the head or handle. In the upper face of said head is formed the busts in relief or medallion portraits of William McKinley and Garrett A. Hobart, the Republican candidates for President and Vice-President of the United States, as shown at D. Upon one side of the head is represented the flag 35 of the United States, as shown at C, while upon the opposite side is shown the figure of an elephant E.

What I claim is—

The design for cane heads or handles substantially as herein shown and described.

In testimony whereof I affix my signature in presence of two witnesses.

FRENCH S. EVANS.

Witnesses:

ALEX. MAHON,

WARREN C. STONE.
